UNITED STATES PATENT OFFICE.

ALBERT L. IDE, OF SPRINGFIELD, ILLINOIS.

GOVERNOR FOR STEAM AND FLUID ENGINES.

SPECIFICATION forming part of Letters Patent No. 319,260, dated June 2, 1885.

Application filed April 22, 1882. (No model.)

To all whom it may concern:

Be it known that I, ALBERT L. IDE, of Springfield, in the county of Sangamon and State of Illinois, have invented certain new 5 and useful Improvements in Governors for Steam and Fluid Engines; and I do hereby declare that the following is a full, clear, and exact description thereof, reference being had to the accompanying drawing, and to the letters of reference marked thereon, which form a part of this specification.

This invention relates to improvements in electric governors for steam-engines, and embraces the novel feature of adjustability where- 15 by the governor may be readily adapted to varying requirements of intensity in the electric current by which it is operated. By this means a greater or less intensity in the lights may be obtained, various forms of lamps re- 20 quiring different intensities of current may be interchangeably used in the circuit, and the number of lamps in the circuit may be varied from time to time, as occasion may require, while the same governor, by means of the ad- 25 justing feature referred to, is capable of being adapted to these several various conditions.

The invention also embraces novel features 30 in the governor-valve, which are sufficiently described to illustrate the operation of the apparatus, but which, being adapted to other situations and uses, may form the subject of a separate application for patent. The distinctive feature of said valve is its adaptability to close the steam-passage by an extreme 35 movement in either direction, as will be further explained.

The invention also embraces certain features of arrangement of the magnet with reference to the axis and stem of the valve, as 40 will also be further explained.

The accompanying drawing shows the governor-valve of the construction herein contemplated located in the steam-supply pipe of an engine, and combined with the electric 45 mechanism and adjusting devices by which the position of the valve is controlled in the operation of the electric current.

A is the governor-valve, and A' is the stop-valve, of the steam-supply pipe. B is the 50 stem of the governor-valve. C is the arch. D

is a hollow helical electro-magnet surmounting the arch, and E is an armature attached to the stem B, and adapted in form and position to enter the spool of the magnet D.

The engine with which the governor is to be 55 used is supposed to drive an electric generator or dynamo of any form, which dynamo may be used exclusively for the purpose of operating the governor, or it may also be connected to supply any desired number of electric lights, 60 or to do any other form of work for which such apparatus is required or adapted. Neither the engine nor the dynamo is here shown, for the reason that the invention contemplates nothing novel in the construction of either, 65 and that the method of connecting the helix D of the governor in the current from the generator is sufficiently indicated in the drawing.

The valve herein shown contains the spe- 70 cial feature of being adapted to close by an extreme movement in either direction. It consists of an open-ended cylinder provided with openings through its sides in its middle portion, and seated within two cylindric seats embracing its opposite ends, said seats being cast in the same piece, but separated by a passage by which the steam is admitted around the central portion of the movable valve between the seats, so as to enter the ports above de- 75 scribed, and find escape at opposite ends of the valve. The valve and its seats are inclosed within a globe-shell in the usual manner of this general class of valves. The valve described can be operated to partially close off the steam 80 from the engine by a movement in either direction, and will be perfectly closed when the central ports are brought wholly within either the upper or the lower cylindric seats. The cylinder is of course constructed of such length 85 that when the central ports are brought into either seat so as to close them the other end at the same time protrudes into the opposite seat and cuts off the supply of steam.

In the application of this valve to the pur- 90 poses of an electric governor, as herein contemplated, it is designed that the ports of the valve shall work in connection with the upper cylindric valve-seat, said ports being closed more or less as the valve is thrown upward by 95 100

the action of the electric current through the magnet; but it is also contemplated that after the engine is shut down, by closing the stop-valve A' in the usual way the valve shall be forced downward so that its ports are closed within the lower seat. It is also contemplated, as will be herein explained, that in case the electric current is broken, or in case the driving-belt of the engine is broken, that the valve 10 will be closed by being thrown downward so that its ports are carried within the lower seat.

In the construction and arrangement here shown the helix D is applied to a hollow spool 15 with its axis coincident with that of the valve-stem B, being mounted fixedly upon the arch C. The insulated wires d d terminate in binding-posts d', fixed to the spool, as shown, one or both of said posts being properly insulated 20 from the spool, and both being adapted to receive the wires d' d'', leading to and from the dynamo, and thereby bringing the helix D into the electric circuit of said dynamo. The valve-stem B is provided with the armature E, after 25 fixed thereto in proper position with reference to the helix to be raised by the latter when the force of the electric current is augmented therein. Said stem is also provided with the fixed collars or shoulders b b', between which 30 projects the branched end of the lever F, pivoted in the arch C at f. The outer end of said lever is connected with the fixed arm G by the contractile spring H, made adjustable as to its tension by the screw-threaded hook I and 35 thumb-nut J.

By depressing the outer end of the lever F the stem B may be raised to bring the valve A into working position, as shown—that is to say, with the ports in the steam-space between 40 the seats. Whenever the speed of the engine becomes too great, the corresponding excessive force of the electric current, operating through the magnet D, will raise the valve and bring its ports partly within the upper seat, and 45 thereby proportionately cut off the steam-supply and lower the speed of the engine. Said stem is also shown prolonged through the upper end plate, D', of the spool, (which serves as a guide therefor,) and provided at its free 50 extremity with a ring, B', by which also the valve may be raised to working position.

The lower shoulder, b, is exclusively used in the operation of the apparatus, being the only one upon which the lever bears by reason 55 of the action of the spring in opposition to the attractive force exerted by the electromagnet on the armature. The upper shoulder is used when in starting the machine it is desired to lift the valve by bearing down 60 with the hand on the outer end of the lever.

By placing the shoulders at a distance apart such as shown, the upper shoulder cannot normally rest on the lever so as to hold the valve up, it being observed that a valve of this class 65 closes by reason of its weight automatically when the current is shut off or broken, and thereby prevents the engine from running

away. The ring, when present at the top end of the valve-stem, may, however, be taken hold of and used as a means for conveniently 70 lifting the valve-stem, in place of depressing the outer end of the lever.

In the use of the particular form of valve shown, or of other forms having similar action, should the current be broken the valve falls 75 by its weight or by its weight re-enforced by the spring H, and closes off the steam-supply by carrying the ports of the cylindric valve into the lower seat.

Not only may the required uniformity of engine-speed be obtained by the means shown under varying work, as in other forms of governor, but in the use of the engine for the purpose of generating electricity for illumination the speed of the engine will be lessened or accelerated automatically when a number of lights are shut off or connected into the circuit. By means of the adjusting device applied to the spring H operating through the lever F, as described, a greater or less intensity in the lights may also be obtained, various forms of lamps requiring different intensities of current may be interchangeably used, and the number of lamps in the circuit may be varied from time to time, as may be 95 desired, the adjustable spring being readily varied in its tension so as to control the valve in opposition to currents of differing power.

After the above description of the devices employed a detailed description of the operation is unnecessary. It is obvious that in the normal working of the machine the action of the magnet is to draw the valve-cylinder upward, so that its ports will be regulated as to their area, and so as to control the amount of steam admitted to the engine in accordance with the force exerted by the magnet upon the armature E, the spring H operating through the lever F to depress the valve and open the ports whenever the force of the current is diminished. While the spring H, however, thus operates in conjunction with the magnetic current, it is plain that when said current ceases, as may happen from a variety of causes, or when a driving-belt breaks or is thrown off its pulleys between the engine and the dynamo, the effect of said spring will be to instantly throw the cylindric valve to its extreme lower position, carrying its ports within the lower seat so as to shut off steam. In other words, the spring H operates to open the ports when the electric current is in action through the magnet D; but in the absence of such current it serves to give the valve a throw of such extent as to close said ports and shut off steam. By using other means to close the valve in case the current is broken or a belt is thrown off, or by omitting all devices for this purpose, the adjustable spring H may be employed with other forms of valve than that here shown, with the same effect as to the variation of force in the magnet D under conditions above mentioned.

It is manifest that a solid-core magnet may

also be employed, if preferred, with only mechanical modifications of the construction shown.

It is further obvious that the governor described may be applied to control an engine through the medium of a variable cut-off by connecting the armature with the rod or other part operating the cut-off mechanism.

I claim as my invention—

- 10 1. The combination, with the steam-supply pipe of an engine, of a regulator-valve comprising two valve apertures or seats, and a movable part constructed to close one or the other of said apertures by either of its two extreme movements, an electro-magnet, an armature secured upon the stem of said valve, and a spring applied to oppose the attractive

force of the electro-magnet upon the armature, substantially as described.

2. The combination, with the steam-supply 20 pipe of an engine, of the valve A, the electro-magnet D, the valve-stem provided with shoulders b b', and carrying the armature, and the pivoted lever F, constructed and organized substantially as described, and for the 25 purposes set forth.

In testimony that I claim the foregoing as my invention I affix my signature in presence of two witnesses.

ALBERT L. IDE.
